ATTORNEY.

UNITED STATES PATENT OFFICE.

ABRAHAM RHEINSTROM, OF CINCINNATI, OHIO.

DESIGN FOR A BOTTLE.

SPECIFICATION forming part of Design No. 20,581, dated March 10, 1891.

Application filed February 11, 1891. Serial No. 381,088. Term of patent 3½ years.

To all whom it may concern:

Be it known that I, ABRAHAM RHEINSTROM, a citizen of the United States, residing at Cincinnati, in the county of Hamilton and State of Ohio, have invented and produced a new and original Design for Bottles, of which the following is a specification, reference being had to the accompanying drawings, forming part thereof.

- 10 Referring to the accompanying drawings, wherein like letters of reference point out similar parts on each figure, Figure 1 is a plan view of a bottle, showing my design. Fig. 2 is a longitudinal sectional view thereof. Fig. 15 3 is a transverse sectional view on the line $x-x$. Fig. 4 is a view of the under surface of the bottom of the bottle, these four views being deemed necessary to fully illustrate my design.
- 20 The leading feature of my design consists in a bottle the body of which is practically quadrilateral in cross-section. The sides A are flat; but the respective points of conjunction compose a curve of the conjoining edges, 25 as seen at a. The upper end of each side is also connected by curves a' to the neck-base B, which base slopes upwardly from each side A toward a common central point. From this base the neck N extends upwardly, the point 30 of connection of the neck and base composing a circumferential inverted curve n. The tubular neck N, springing upwardly from its base, is not of equal diameter its whole length, but tapers toward the collar C.
- 35 The bottom D of the bottle is a plane having a circumferential section d upwardly inverted. The four sides of the bottom D are each curved upwardly where meeting the lower line of each side A, composing at such 40 points of juncture curves d', similar in contour to the curves a at the juxtaposed edges of the sides.

The neck-base B inclines downwardly from the neck N until meeting the upper end of the respective sides A, and is also obliquely inclined in direction of each of the four curved edges a, and thereat the diverging and converging lines meet and compose hemispherical curves. (Indicated in the drawings by arrows.)

The downwardly-inclined surface of the neck-base diverges forwardly toward one side A and laterally toward two opposite sides, whereby the upper end of each of said sides composes a flat arch integral with said neck-base and the main body.

A longitudinal section through any portion of the body will present a flat arch with straight vertical supporting-lines both on inner and outer surfaces, and a transverse section presents a quadrangle the corners of which are curved, the inner and outer surfaces being in parallel alignment.

It will be understood by the foregoing description and the drawings in illustration thereof that every point of connection of the four sides of the body where they meet and where their lower ends conjoin the bottom, as well as where they connect with the neck-base, is curved or rounded, as shown at a a' 65 d', and that the neck uprising from its base has an invertedly-curved connection thereto, as seen at n, and that although the main chamber is practically quadrangular none of the meeting-points of any of the sections 70 thereof compose angles.

I claim—

A bottle having the configurative contour as illustrated and described.

ABRAHAM RHEINSTROM.
